US00D477714S

(12) **United States Design Patent** (10) Patent No.: **US D477,714 S**
 Cunningham et al. (45) Date of Patent: ** Jul. 29, 2003

(54) **DRILL BIT CASE**

(75) Inventors: **Ian W. Cunningham**, Matthews, NC
 (US); **Kristofor M. Hallee**,
 Huntersville, NC (US)

(73) Assignee: **Irwin Industrial Tool Company**,
 Freeport, IL (US)

(**) Term: **14 Years**

(21) Appl. No.: **29/168,433**

(22) Filed: **Oct. 2, 2002**

(51) LOC (7) Cl. **03-01**

(52) U.S. Cl. **D3/273; D3/294; D3/905**

(58) Field of Search D3/273, 276, 281,
 D3/282, 294, 295, 905, 302; D9/420, 424,
 423; 206/349, 372, 373, 377, 378, 379

FOREIGN PATENT DOCUMENTS

DE 1 085 810 7/1960

Primary Examiner—Philip S. Hyder

(74) Attorney, Agent, or Firm—Brinks Hofer Gilson & Lione

(57) **CLAIM**

The ornamental design for a drill bit case, as shown and described.

DESCRIPTION

FIG. 1 is a perspective view of an embodiment of the drill bit case;

FIG. 2 is a top view of the embodiment of FIG. 1;

FIG. 3 is a bottom view to the embodiment of FIG. 1;

FIG. 4 is a side view of the embodiment of FIG. 1; and,

FIG. 5 is a front view of the embodiment of FIG. 1.

The dotted lines indicate components for illustrative purposes only and form no part of the subject design.
